(57) **CLAIM**

The ornamental design for interactive computer, as shown and described.

DESCRIPTION

- FIG. 1 is a front perspective view of an interactive computer wherein the pad is detached;
FIG. 2 is a rear perspective view thereof;
FIG. 3 is a front view thereof;
FIG. 4 is a rear view thereof;
FIG. 5 is a left view thereof;
FIG. 6 is a right view thereof;
FIG. 7 is a top view thereof;
FIG. 8 is a bottom view thereof;
FIG. 9 is a front perspective view of an interactive computer wherein a pad is attached;
FIG. 10 is a rear perspective view thereof;
FIG. 11 is a front view thereof;
FIG. 12 is a rear view thereof;
FIG. 13 is a left view thereof;
FIG. 14 is a right view thereof;
FIG. 15 is a top view thereof; and,
FIG. 16 is a bottom view thereof.

(Continued)

The broken lines shown in the drawings are for environment only and form no part of the claimed design.
